UNITED STATES PATENT OFFICE.

BRUCE C. WHITE, OF NEW YORK, N. Y., ASSIGNOR TO R. HOE AND CO., OF NEW YORK, N. Y., A CORPORATION OF NEW YORK.

CLEANING DEVICE FOR PRINTING-MACHINE INKING MECHANISM.

1,269,767.

Specification of Letters Patent. Patented June 18, 1918.

Application filed October 9, 1915. Serial No. 54,928.

To all whom it may concern:

Be it known that I, BRUCE C. WHITE, a citizen of the United States, residing at New York, county of New York, and State of New York, have invented certain new and useful Improvements in Cleaning Devices for Printing-Machine Inking Mechanism, fully described and represented in the following specification and the accompanying drawings, forming a part of the same.

This invention relates to certain improvements in inking mechanism for printing machines, and particularly to that type of inking mechanism in which the ink is distributed by means of a plurality of nozzles, a nozzle being provided for each column or section of the form, the ink being delivered to these nozzles under pressure, which may be produced by a series of pumps. In this type of inking mechanism the ink is delivered by the nozzles through small orifices and it sometimes occurs that these orifices become choked or stopped up by ink, due to the press being out of operation for a certain length of time. It also sometimes occurs that due to the presence of clots or skins in the ink, the orifices will be stopped up while the machine is operating. Because of this liability to stoppages, especially when the mechanism is running, it is necessary for the attendant to examine the delivery orifices from time to time to see if the ink is being properly delivered, or papers will be spoiled. When a stoppage occurs it is necessary to clean the orifice with a piece of wire or other tool. If several of the orifices become stopped up, this method of cleaning requires time to perform, and this method of cleaning orifices is for this and other reasons unsatisfactory.

It is the object of the present invention to produce a construction of simple form, by which in a machine employing a plurality of ink delivery nozzles or orifices all the nozzles or orifices may be simultaneously cleared from time to time by the attendant, and a construction of such character that

when the mechanism is not being operated, the device may be used to close up the nozzles and thus keep the ink from drying in them and stopping them up.

For a full understanding of the invention a description will be given of the preferred form of an apparatus embodying the same in connection with the accompanying drawings, in which—

Figure 1 is a side elevation, partly in section, of so much of an inking mechanism of the type referred to as is necessary for a full understanding of the invention, and

Fig. 2 is an end view, partly broken away, of the mechanism shown in Fig. 1, looking toward the left in that figure, the distributing cylinder being omitted.

The inking mechanism with which the mechanism shown is especially designed for use is fully shown and described in my prior application Serial No. 38,528, and only so much as is necessary for a full understanding of the present invention is here shown, and this will be only briefly described.

Referring to the drawings, there are provided a plurality of supply conduits or pipes 1 to which ink is delivered under pressure from a reservoir provided with a plurality of pumps, one for each ink conduit, these pumps, the reservoir and connections to the conduits not being shown. These ink conduits or supply pipes have their delivery ends arranged in line along a distributing cylinder 2, being grouped in a casing 3 which has a removable cover 4 to provide for ready access to the pipes. The wall 5 of the casing adjacent the distributing cylinder is provided with openings therethrough receiving the ends of the pipes, the ink passing to the nozzles supplying the distributing cylinder through these openings.

In the construction shown, the nozzles deliver through these openings into narrow passages 6 outside the front wall of the casing, in which passages the ink is distributed sidewise from the pipes to substan-

tially the extent of the column or other section to be supplied with ink. These passages 6 in the particular construction shown, have small delivery orifices 7, a sufficient number of which are formed on each passage to secure the required distribution, and the ink from these openings falls down the inclined face 8 of a nozzle bar or plate 9 mounted on the outer side of the casing 5 and acting to form the outer wall of the passages 6 before described, this bar also acting to divide these passages from each other to column or other form section width. The inclined surface 8 extends substantially into contact with the distributing cylinder 2 and the ink from the orifices 7 spreads in flowing down the incline so as to form a continuous thin stream or layer of ink in contact with the distributing cylinder. These small orifices 7, as before stated, are liable to become stopped up or plugged up with ink, and in accordance with the present invention means are provided whereby these nozzles can be simultaneously cleared all along the cylinder from time to time by the attendant, so that the necessity for examining them is done away with and a free and clear distribution of ink from all the nozzles is assured, and, in the event of several of the nozzles becoming stopped up or plugged, they can all be cleared at once, and the time consumed in separately cleaning them is saved. While the particular construction for effecting this may be varied, in the preferred embodiment of the invention there will be provided a plurality of cleaner or ejector pins 10, one pin being provided for each orifice. These ejector pins are mounted in alignment with the orifices and operate so as to simultaneously move into the orifices, the pins being dimensioned to snugly fit the orifices and effectually remove from them any foreign material which may cause stoppage. A convenient construction which may, however, be varied in its details, for effecting the simultaneous movement of the ejector pins is that shown in the drawings. As illustrated the pins are carried on a bar 11 extending across the distributing mechanism, the pins passing through holes in the nozzle piece or bar 9 before referred to. These holes in bar 9 are in alignment with the orifices and are of sufficient depth to act as a guide for the pins when they are moved so as to insure their proper movement into the orifices, the nozzle piece 9 being provided with a depending portion 12 in which these holes are formed. In the particular construction illustrated, the orifices 7 are arranged vertically and the pin-carrying bar 11 is given a lifting movement to move the pins in and out of the orifices. As

shown, this movement is effected by mounting the bar 11 in a pair of brackets 13, 14, secured to the casing 3, the bar being vertically movable in its brackets. Also mounted in these brackets and extending across the machine is a shaft 15 which has collars 16, 17 fast thereon, these collars being provided with extensions or lugs 18 taking into slots in the bar 11. The shaft is rotated and the bar 11 lifted by means of a suitable handle 19. If desired, springs 20, taking between the brackets and the collars may be employed for cushioning the upward movement of the ejector pins and assisting to some extent in the return therof.

With this construction, all the nozzles can be cleared of ink simultaneously by the attendant by simply manipulating the handle, and this can be done so frequently as to obviate the necessity for examining the nozzles. This construction is an especially convenient one for the upper decks of machines where there are two or more decks of inking mechanism, in that the ejector bar operating handle may be located on the floor and the ejector bars of each deck connected by rods, so that all can be operated simultaneously. Furthermore, the nozzles can be completely sealed by the ejector pins when the machine is not being operated.

While the invention has been shown in connection with a plurality of nozzles having small ink delivery openings, it will be understood that the invention is capable of use with other forms of nozzles and is not to be restricted to the particular form shown and described.

What is claimed is:

1. In an inking mechanism for printing machines, the combination with a plurality of unobstructed ink delivery nozzles, of an ink distributing surface to which the nozzles deliver, a plurality of separate cleaning devices, and means for operating the cleaning devices simultaneously for clearing the nozzles.
2. In an inking mechanism for printing machines, the combination with a plurality of unobstructed ink delivery nozzles, of an ink distributing surface to which the nozzles deliver, a plurality of ejector pins, and means for moving the pins into the nozzles.
3. In an inking mechanism for printing machines, the combination with a plurality of ink delivery nozzles each having a series of small delivery orifices, of an ink distributing surface to which the nozzles deliver, a plurality of ejector pins dimensioned to snugly fit and close the orifices, and means for moving the pins into the nozzles.
4. In an inking mechanism for printing machines, the combination, with a plurality of ink delivery nozzles and an ink distribut-

ing surface to which the nozzles deliver, of means mounted adjacent thereto and arranged to be moved into the nozzles for sealing the same, and mechanical operating means for moving the sealing means into and out of the nozzles.

In testimony whereof, I have hereunto

set my hand in the presence of two subscribing witnesses.

BRUCE C. WHITE.
